THOMAS CARRICK, OF SAN FRANCISCO, CALIFORNIA.

LUBRICATING-CUP FOR STEAM-CHESTS AND THE LIKE.

No. 921,201.

Specification or Letters Patent.

Patented May 11, 1908

Application filed June 24, 1908. Serial No. 440,150

To all whom it may concern:

Be it known that I, THOMAS CARRICK, citizen of the United States, residing at the city and county of San Francisco and State of California, have invented new and useful Improvements in Lubricating-Cups for Steam-Chests and the Like, of which the following is a specification.

This invention relates to lubricating devices, and pertains especially to means for automatically regulating the feed of graphite or other lubricant to a cylinder, steam chest, or the like.

The invention consists of the parts and the construction and combination of parts as hereinafter more fully described and claimed, having reference to the accompanying drawings, in which:

Figure 1 is a central section of the device. Fig. 2 is an elevation of the valve. Fig. 3 is a bottom plan of same. Fig. 4 shows the device as applied to a steam chest. Fig. 5 shows a modification.

A represents a cup or other suitable receptacle for holding graphite or the like. This cup is screwed into or otherwise attached to a steam chest or cylinder, the interior of which it is desired to lubricate. The top of the cup may be closed by any suitable means, and the bottom of the cup has an outlet opening into the interior of the steam chest or cylinder, with a double-ended sectional valve 3 adapted to seat in the bottom opening of the cup. This valve 3 is double-seating, and the two sections of the valve are held together by a bolt 4 passing centrally through the sections, and the set nuts 5 screwing on to the bolt. The bodies of the valve sections are recessed or grooved longitudinally, as represented at 6, to provide lubricating ducts for the discharge of the lubricant periodically from the cup into the cylinder. These grooves or ducts in the two sections are adapted to be brought into register, or carried to one side or the other, more or less out of register, by turning one valve section relative to the other, for the purpose of restricting or enlarging these lubricating ducts, and thereby control the feed of the lubricant to the cylinder. Each valve section adjacent to its seating end may be provided with an annular groove 7 con-

necting the several ducts 6. The abutting ends of the sections are provided with suitable interlocking means by which the size of the ducts may be maintained uniform after proper regulation. The interlocking means here shown, consists of a dowel-pin 8 in the inner end of one section registerable with one or other of the holes 9 in the abutting end of the opposite section. The mean width of the grooves is widened or narrowed, according to which hole 9 the pin 8 is inserted into.

In practice, the pressure in the cylinder or steam chest, whether from steam, air, gas or other fluid, exerted against the under side of the valve lifts the valve to close it against its lower seat 10, thereby allowing the lubricant, such as graphite, to drop into the grooves of the valve. As soon as the pressure in the cylinder or chest is released, so that the valve may drop by gravity, the latter closes over its upper seat 11, thereby preventing any more lubricant entering the grooves, but allowing the charge of lubricant in the grooves to drop into the cylinder or chest.

In order to prevent the splashing of the graphite when the valve opens downward to let the charge of graphite drop out of the grooves, and to enable, also, a suitable lubricating oil to be mixed with the graphite before it enters the steam chest or cylinder, I may employ a supplemental plug, as 12, into the top of which the cup A may screw; this plug in turn screwing into the steam chest or cylinder.

The interior of the cup just below the valve has a chamber 13 and a downward discharge outlet 14. Entering chamber 13 is a suitable oil pipe 15 through which oil is admitted in suitable quantities and at suitable intervals. In this case the charge of graphite is deposited first in chamber 13 and therein mixed with oil, so that the commingled oil and graphite feeds downward into the steam chest or cylinder.

In Fig. 4, I have shown the invention applied to a locomotive steam chest, with the plug 12 screwing into the top of the steam chest cover 16. The bottom of valve 3 is in this case acted on to close the valve so long as the live steam is in the chest, but whenever the engine stops, or the steam is turned off, the valve drops and deposits its charge of

graphite into the chest, whence it works around the valve and thence into the cylinder. The size of the ducts 6 is regulated so as to deliver a suitable supply of graphite whenever the valve is allowed to drop. As a matter of fact, the action of the valve 3 is not continuous, and need not be, since the occasional starting and stopping of the engine provides for a sufficient quantity of graphite to pass into the steam chest and cylinder.

For stationary engines, or elsewhere where it is desired to periodically feed a definite quantity of graphite and oil, the cup A with its pressure-operated valve may screw into a valve casing 17 which has a plug valve 18 by which the pressure from the chest 19 may be controlled so as to allow the valve 3 to open or close. The top of the casing 17 has a pet-cock 20. Ordinarily with plug 18 turned so that the pressure from the steam chest may act on the under side of the valve 3, the pet-cock 20 is closed. With the valve 3 thus lifted, the grooves are allowed to fill; the sections of the valve being turned so as to make the grooves the desired size to contain the desired quantity of graphite which is to be delivered periodically. When the plug 18 is turned to shut off communication with the chest, the pet-cock 20 is opened to relieve the pressure in the casing 17, thereupon allowing the valve 3 to drop and deposit its charge into the casing 17. The cock 20 is then closed and valve 18 opened, thereby lifting and closing valve 3, but allowing the charge of graphite now in casing 17 to pass on down into the steam chest and cylinder.

Having thus described my invention, what I claim and desire to secure by Letters Patent is—

40 1. A lubricating cup having an outlet passage, a double-seating valve in said passage, said valve having longitudinal grooves between its ends, and means for restricting or enlarging said grooves.

45 2. A lubricating cup having a passage-way communicating with the interior of the part to be lubricated, a double-ended valve in said passageway, said valve adapted to seat upward on the exertion of pressure on the under side of the valve and seating downward by gravity, and having lubricating ducts between its ends, and means for restricting or enlarging said ducts.

50 3. A lubricating cup having a discharge opening, a valve fitting said opening, said valve comprising symmetrical alined sections, each section having a seating portion, the body of the sections having longitudinal registerable grooves, and connecting means passing through the sections and permitting the sections to have a turnable movement to widen or narrow said grooves.

55 4. A lubricating cup having a discharge opening, a valve fitting said opening, said valve comprising symmetrical alined sec-

tions, each section having a seating portion, the body of the sections having longitudinal registerable grooves, connecting means passing through the sections and permitting the sections to have a turnable movement to widen or narrow said grooves, and interlocking means on the abutting ends of the sections. 70

5. A lubricating cup having a discharge opening, a valve fitting said opening, said valve comprising symmetrical alined sections, each section having a seating portion, the body of the sections having longitudinal registerable grooves, connecting means passing through the sections and permitting the sections to have a turnable movement to widen or narrow said grooves, and a male locking member on one section fitting corresponding openings on the adjacent section. 75

6. A lubricating cup having a double-ended valve controlling discharge therefrom, said valve having longitudinal ducts, said valve transversely sectioned, and means for holding the sections together and to permit a turnable movement of one section relative to another to widen or narrow the ducts. 80

7. The combination of means inclosing a chamber having an inlet and outlet, a valve in the chamber controlling communication between the inlet and outlet, a valved vent on the inlet side of said valve, said outlet connected with a source of variable fluid pressure; and a graphite cup connected with the inlet, said cup having a fluid-pressure-actuated double-ended sectional valve, the sections of which are turnable one relative to the other to restrict or enlarge the passage for the lubricant. 95

8. The combination of a plug having a collection chamber, said chamber having an outlet, a graphite cup screwing into the plug and discharging into said chamber, a double-ended, lengthwise-grooved, sectional, fluid-pressure-actuated valve in said cup, and means whereby the sections of the valve may be axially turned one relative to the other to widen or narrow the grooves. 105

9. The combination of a plug having a collection chamber, said chamber having an outlet, a graphite cup screwing into the plug and discharging into said chamber, a double-ended, lengthwise-grooved, sectional, fluid-pressure-actuated valve in said cup, means whereby the sections of the valve may be axially turned relatively to each other to widen or narrow the grooves and an independent oil supply pipe entering said chamber. 115

10. A lubricating cup comprising a lubricant holding casing with filling inlet and discharge outlet, a lubricant filling and discharging valve device located between said inlet and outlet, said valve device being double-ended and having longitudinal grooves between its ends, said device intermittently 125

filling and discharging said lubricant in and through the discharge outlet by applying and releasing the pressure respectively to and from said device, and means for restricting 5 or enlarging said grooves to vary the amount of lubricant passing in and through the discharge outlet.

In testimony whereof I have hereunto set my hand in presence of two subscribing witnesses.

THOMAS CARRICK.
